UNITED STATES PATENT OFFICE.

JULES FARNAN, OF NEW YORK, N. Y.

DESIGN FOR A BOTTLE.

SPECIFICATION forming part of Design No. 32,283, dated February 27, 1900.

Application filed February 2, 1900. Serial No. 3,750. Term of patent 14 years.

To all whom it may concern:

Be it known that I, JULES FARNAN, a citizen of the United States, and a resident of New York city, county and State of New York, 5 have invented a new and original Design for Bottles, of which the following is a specification, reference being had to the accompanying drawings, in which—

Figure 1 is a side elevation of my newly-designed bottle. Fig. 2 is a cross-section on line 2 2, Fig. 1.

The leading feature of my design consists of a bottle having a body *a*, that is substantially cylindrical and tapers at its upper end, 15 as at *a'*. This tapering upper end is sur-

rounded by a row of lenticular figures *b*, below the flanged neck *a'*. A similar row of lenticular figures *c* is formed around the body *a* a short distance above its base.

What I claim is—

The design for a bottle, substantially as herein shown and described.

Signed by me at New York city, county and State of New York, this 1st day of February, 1900.

JULES FARNAN.

Witnesses:

WILLIAM SCHULZ,
F. V. BRIESEN.
